UNITED STATES PATENT OFFICE.

WARREN F. FRASER, OF WESTBORO, MASSACHUSETTS.

MECHANICAL MOVEMENT.

1,424,397.

Specification of Letters Patent. Patented Aug. 1, 1922.

Application filed September 25, 1919. Serial No. 326,272.

To all whom it may concern:

Be it known that I, WARREN F. FRASER, a citizen of the United States, residing at Westboro, in the county of Worcester and State of Massachusetts, have invented new and useful Improvements in Mechanical Movements, of which the following is a specification.

This invention relates to improvements in mechanical movements for imparting a reciprocatory motion to a member of a machine and is particularly adapted to grinders, lathes and machine tools having a reciprocating work carrying table.

15 The object of the invention is to impart a reciprocatory motion to the work table of a grinder or other machine tool which will gradually decrease the speed of the table at each end of its stroke and will start the 20 table in an opposite direction at a gradually increasing speed without any change being necessary in the speed of the main driving shaft, whereby a heavy and quickly moving member, such as the work table of 25 a grinder, may be gradually brought to a stop when moving in one direction and gradually started to move in the opposite direction.

The invention consists particularly in an 30 improved mechanism for bringing the table to a gradual stop and for gradually starting its movement in an opposite direction.

The invention further consists in mechanism whereby the mechanism which reciprocates the work table may be easily and 35 quickly changed to be operated either by power or by hand.

The invention consists, further, in the combination and arrangement of parts set 40 forth in the following specification and particularly pointed out in the claims.

Referring to the drawings:

Figure 1 is a front elevation of my improved grinder.

Fig. 2 is a sectional plan on an enlarged scale taken on line 2-2 of Fig. 1.

Fig. 3 is a sectional elevation taken on line 3-3 of Fig. 1, and partly broken away.

Fig. 4 is a sectional elevation taken on 50 line 4-4 of Fig. 2.

Fig. 5 is a sectional elevation taken on line 5-5 of Fig. 1.

Fig. 6 is a sectional elevation taken on line 6-6 of Fig. 1.

55 Like numerals refer to like parts throughout the several views of the drawings.

In the drawings, 10 is the frame of the machine. 11 is a reciprocatory table upon which is mounted a head-stock 12 and tail-stock 13 upon which the work to be operated 60 upon is mounted in the usual well known manner. 14 is a rotary grinder or emery wheel rotatably mounted upon a head 15 which is slidably mounted upon the frame 10 and is moved transversely of the reciprocatory table 11 by a nut 16 which engages a screw-threaded shaft 17 rotatably mounted upon the frame of the machine, and the nut 16 engages an arm 18 which projects downwardly from the grinder head 15. 70

A movement transversely of the table 11 is imparted to the grinder by a ratchet 19 fast to the screw-threaded shaft 17, said ratchet being rotated intermittently by a pawl 20 mounted on a lever 21 which is pivoted at 22 to the frame of the machine and has a rocking movement imparted thereto by a lever 23 which is provided with a laterally extending arm 24, upon the free end of which is journaled a roll 25 which is adapted to engage screws 26 and 27 when the lever 23 is rocked as hereinafter set forth. When said lever 23 is rocked the roll 25 moves upwardly and downwardly engaging the screws 26 and 27 and imparting a rocking movement to the lever 21, whereby the ratchet 19 has an intermittent rotary movement imparted thereto by the pawl 20, thus intermittently rotating the shaft 17 and through the nut 16 and arm 18 the grinder 90 frame and its wheel are moved step by step transversely of the table 11. 85

The table is moved alternately in opposite directions by mechanism which will now be explained.

95 28 is the main driving shaft of the machine and is rotated by any suitable means such as a pulley in the direction of the arrow *a* (Fig. 2). Said main driving shaft has two gears 29 and 30 fast thereto. The gear 29 meshes into a gear 31 which is loosely mounted upon a shaft 32 to which is fastened a worm 33. The gear 30 meshes with an intermediate gear 34 which, in turn, meshes with a gear 35 rotatably mounted upon the 100 shaft 32. The gears 31 and 35 are alternately locked to the shaft 32 by a reciprocatory clutch member 36 which is provided on its opposite ends with teeth 37 and 38 adapted to engage teeth 39 and 40 on the gears 35 110 and 31, respectively.

The clutch member 36 is splined to the

shaft 32 so that it can be reciprocated on said shaft but is locked against rotary movement thereon, so that when the teeth 37 on the clutch are brought into engagement with the teeth 39 on the gear 35 the shaft 32 will be rotated in one direction and when said clutch member is moved so as to bring the teeth 38 into engagement with the teeth 40 on the gear 31, then the shaft 32 will be rotated in the opposite direction. Thus by moving the clutch member alternately into engagement with the teeth 39 or the teeth 40 the worm 33 will be rotated alternately in opposite directions.

The worm 33 meshes with a worm gear 41 (Figs. 3, 4 and 6) which is fastened to a spur gear 42 which meshes with a rack 43 fast to the table 11. A rack 43' also fast to the table 11 has fastened thereto plates 109 and 110 provided with tappet screws 111 and 112 which have screw-threaded engagement with said plates and are adapted to alternately engage, near the extreme end of the movement of the rack 43' and table 11, a stud 113 slidably mounted in the lever 23.

The worm gear 41 and the spur gear 42, therefore, rotate as one piece and are rotatably mounted upon an eccentric pin 44 projecting from the inner end of a rock-shaft 45 which is journaled in an auxiliary frame 46, said frame having mounted thereon the mechanism which is hereinafter described for actuating the reciprocating table 11 and for gradually stopping and starting said table.

The rock-shaft 45 has an arm 47 fast thereto (Figs. 1, 3 and 6) and this arm has a cam roll 48 mounted on its free end and engaging a cam slot 49 provided in the lever 23. The lever 23 is pivoted at 50 to the auxiliary frame 46 and is normally held in the position illustrated in Fig. 1, that is, in a centrally located position, by spring actuated pins 51 and 52 slidably mounted in a bracket 53 fast to the auxiliary frame 46 (Figs. 1 and 3). The pins 51 and 52 are each in its uppermost position when the lever 23 is in its neutral position as illustrated in Fig. 1 and said pins are stopped in the positions illustrated in Fig. 1 by the nuts 54 and 55 having screw-threaded engagement therewith and adapted to engage the bracket 53.

The clutch member 36 is shifted to lock the gear 31 or the gear 35 to the shaft 32 by mechanism which will now be described, consisting of a stud 56 (see Figs. 1 and 2) which is fastened to the lever 23 and projects rearwardly therefrom through an opening 57 in the auxiliary frame 46. The inner free end of said stud 56 is arranged to play between two pins 58 and 59 which are, respectively, actuated by springs 60 and 61. Said pins 58 and 59 are slidably mounted 65 upon a sliding frame 62 which is arranged to

slide upon a stationary shaft 63 fast to the auxiliary frame 46. Said sliding frame has an ear 64 to which is fastened a bifurcated arm 65 which engages a slot 66 formed in the periphery of the clutch member 36, so that as the frame 62 is moved in opposite directions, as hereinafter described, the clutch member 36 will be moved with it.

A rocker frame 67 (Figs. 2, 3 and 4) and also shown in dotted lines Fig. 1, is pivoted at 68 to the auxiliary frame 46. This rocker frame 67 is located adjacent the inner face of the front plate of the auxiliary frame 46 and has an opening 69 extending therethrough through which the stud 56 projects. Said rocker frame 67 is normally locked in position by means of a pin 70 (Fig. 4) which is adapted to project into a notch 71 provided in an arm 72 which is fastened to a rocker-shaft 73 to which a rocking motion may be imparted by means of an arm 74 fast thereto and connected by a link 75 to an arm 76 fast to a shaft 77 which is operated by means of a hand lever 78 (Fig. 5).

It will be noted that the notch 71 opens out of the upper edge of the arm 72 and is provided with oppositely inclined edges 79 and 80.

The distance to which the rocker frame 67 can move is limited by a stop pin 81 which is fastened to the front plate of the auxiliary frame 46 (Fig. 3), said rocker frame being provided with a notch 82 in its lower edge into which the pin 81 projects.

The sliding frame 62 is locked in position against movement toward the right (Fig. 2) by a tripper lever 83 which is pivoted at 84 to the rocker frame 67 and the front end 83' of said tripper lever is adapted to engage the right hand edge (Fig. 4) of a plate 85 which is fastened to the slide frame 62 (see Fig. 3). Said slide frame 62 is locked at certain times against movement toward the left (Fig. 4) by another tripper lever 86 which is pivoted on a pin 87 fast to the rocker frame 67, and at certain times in the operation of the machine, as hereinafter described, the front end 86' of the tripper lever 86 will engage the left hand side of the plate 85 and prevent the slide frame 62 from being moved toward the left (Figs. 2 and 4) by the spring 60. The tripper levers 83 and 86 are joined together by a tension spring 88.

The stud 56 is provided with two tripper screws 89 and 90 which have screw-threaded engagement with said stud and are adapted alternately to engage the tripper levers 83 and 86, respectively.

When it is desired to operate the table 11 by hand instead of by power, it is accomplished by rocking the shaft 77 by means of the hand lever 78, rocking said shaft for this purpose in the direction of the arrow b (Fig. 4), which, through the link 75 and 130

arm 74, will rock the rocker shaft 73 in the opposite direction to that of the arrow *b* and this will cause the arm 72 to be moved downwardly and disengage the pin 70, 5 whereupon the rocker frame 67 will be free to rock to a limited extent upon its pivot 68, the extent of said rocking movement being limited by the pin 81. At the same time that the arm 72 is thus moved downwardly 10 (Fig. 4) another arm 91 fast to the rock-shaft 73 will be rocked downwardly and said arm has a notch 92 in its lower edge which will then engage a pin 93 fast to the slide frame 62 (Figs. 3 and 4). The arm 91 15 has oppositely diverging edges 94 and 95 which are adapted to engage the pin 93, according to the position of the slide 62 and move said slide toward the right or left, as the case may be, but as shown in Fig. 2 to 20 toward the right, and thus through the bifurcated arm 65 the clutch member 36 will be moved out of engagement with the gear 35 and into a neutral position between the gears 31 and 35. Thus the power driving mechanism 25 is thrown out of action.

When the hand lever 78 is turned in the direction of the arrow *b*, the shaft 77 will be rocked as hereinbefore set forth and this will move a cam lever 96 fast to the rear 30 end thereof (Fig. 5). Said cam lever has an inclined segmental arm 97 on the lower end thereof which engages a pin 98 and said pin is slidably mounted in a shaft 99, said shaft being rotatably mounted in a bushing 100 in the auxiliary frame 46. A spline 101 is fastened to the pin 98 and projects into a slot 102 formed in said shaft 99.

A spiral gear 103 is rotatably mounted on the shaft 99 and is provided with a keyway 104 into which the spline 101 is adapted to move when the pin 98 is moved toward the left by a spiral spring 105 located in a recess 106 in the shaft 99.

When the cam segment 97 is moved by the 45 lever 96 and by the hand lever 78, as hereinbefore set forth, the pin 98 will be moved toward the left (Fig. 5) by the spring 105 from the position illustrated in Fig. 5 until the spline 101 moves into the keyway 104 and 50 thus locks the gear 103 to the shaft 99. The spiral gear 103 meshes with a spiral gear 107 fast to the worm shaft 32.

The shaft 99 has a hand wheel 108 fast thereto by means of which said shaft may 55 be rotated, and when the parts are in the relative positions just described, with the clutch 36 thrown out of engagement with the power driven gears 31 and 35, said gears 103 and 107 may be rotated by rotating the hand 60 wheel 108 and when so rotated the worm 33 will be rotated, thus rotating the worm gear 41 and the gear 42 and imparting movement to the rack 43 and table 11.

The general operation of the mechanism 65 hereinbefore specifically and to some extent

in general described is as follows: Assuming the parts to be in the relative positions illustrated in the drawings, with the lever 23 in its neutral position, the clutch 36 in engagement with the gear 35, the notch 71 70 in the arm 72 engaging and holding in a fixed position the rocker frame 67, the tripper lever 83 engaging the right hand side of the plate 85 upon the slide frame 62 and the main driving shaft 28 rotated in the direction of the arrow *a*, then the shaft 32 and worm 33 will be rotating in the direction of the arrow *c* (Fig. 2) and the worm gear 41 and spur gear 42 will be rotated in the direction of the arrow *d* (Fig. 4) while the 75 rack 43 and table 11 will be moving in the direction of the arrow *e*. When the rack 43 and the table 11 arrive at a point near the end of the movement of the table 11 in the direction of the arrow *e*, the screw 111 will 80 engage the roll 113 and rock the lever 23 upon its pivot 50 in the direction of the arrow *e*. This will cause the roll 48 to be moved downwardly in the cam path 49 to the lower end of said cam path in the direction of the arrow *f* and will move the 85 rocker shaft 45 and its eccentric pin 44 in the opposite direction to that of the arrow *e* and in the opposite direction to that of the movement of the table 11 and rack 43 90 and in the opposite direction to the direction of movement of that portion of the gears 41 and 42 adjacent to the rack 43, thus neutralizing or counteracting the effect 95 of the rotary motion of said gears upon the 100 rack 43 and acting as a cushion to bring said rack 43 and table 11 to a gradual stop. While this counteracting influence upon the movement of the table is taking place and while the lever 23 is being moved in the direction of the arrow *e*, the stud 56 will be moved in the same direction and will move the pin 59 toward the right (Fig. 2), compressing the spring 61 until the tripper screw 89 engages the tripper lever 83 and 105 tipping said lever upon its pivot 84 will lift the end 83' of said lever out of engagement with the plate 85, whereupon the slide 62 will be freed and will be moved toward the right (Fig. 2) by the spring 61 and by so 110 moving will move the bifurcated arm 65 in the same direction, together with the clutch member 36, thus moving the clutch member 36 out of engagement with the teeth 39 on the gear 35 and bringing the teeth 38 on said 115 clutch member into engagement with the teeth 40 on the gear 31, whereupon the movement of the slide 62 toward the right will be stopped and the end 86' of the tripper lever 86 will drop into engagement with the left 120 hand side of the plate 85 and lock said slide 62 and the clutch member 36 in another new position, whereupon the shaft 32 will be rotated by the gears 29 and 31 in a direction 125 reverse to that of the arrow *c* and the direc- 130

tion of rotation of the gears 41 and 42 will be reversed to drive the rack 43 and the table 11 in a direction opposite to that of the arrow *e*.

5 As soon as the rack 43 and table 11 begin to move toward the left (Fig. 1) the lever tappet 111 will move in the same direction and the lever 23 will be moved to its neutral position by the spring actuated 10 pin 51 and the rocker arm 47 will be moved back to the position illustrated in Fig. 1; thus moving the rock-shaft 45 and its eccentric pin 44 back to their original positions, and in the opposite direction to the direction 15 in which that portion of the gears 41 and 42 adjacent to the rack 43 is being rotated at that time, thus neutralizing and counteracting to a certain extent the movement of the rack 43, so that it will start 20 to move the table 11 slowly, and gradually said movement will increase until the full driving effect of said gears 41 and 42 will be accomplished.

The shape of the cam slot 49 is so designed 25 as to assist in the gradual stopping of the reciprocatory movement of the rack 43 and table 11 and also to assist in the gradual starting of said table in the opposite direction to that in which it was formerly moving 30 before it stopped. When the table 11 is arriving near the extreme end of its movement in the opposite direction to that of the arrow *e*, the tappet screw 112 will engage the roll 113 on the lever 23 and said 35 lever will be tipped in the opposite direction to that in which it was tipped when the roll 113 was engaged by the tappet screw 111 and the roll 48 will then be moved upwardly in the cam slot 49 and rock the 40 arm 47, with its eccentric rock-shaft 45, in the opposite direction to that hereinbefore described, thus moving the gears 41 and 42 in the opposite direction, but as the rack 43 is now moving in the opposite 45 direction to that in which it was moving when the same was being previously considered, it will be seen that the result of stopping the rack gradually and of starting it gradually will be the same at both ends 50 of the movement of the table and that the shifting of the clutch will be reversed when the tripper lever 86 is disengaged from the plate 85 and the slide frame 62 moved toward the left by the spring 60 which has 55 been compressed by the stud 56 engaging the pin 58.

When it is desired to move the table by hand, the power mechanism is thrown out of action, as hereinbefore described, by rocking 60 the hand lever 78 which thus rocks the shaft 77 and through the link 75 moves the arm 74 to rock the shaft 73 and disengage the arm 72 from the pin 70, leaving the rocker frame 67 free to swing to a limited extent 65 upon its pin 68 and bringing one of the

edges 94 or 95 of the notch 92 on the arm 91 into engagement with the pin 93, whereupon the slide frame 62 will be moved to position the clutch member 36 midway between the gears 31 and 35 and will be locked 70 in that position, and when said hand lever 78 is thus rocked the spiral gear 103 will be locked to the shaft 99. The table may then be moved as desired by rotating the hand wheel 108. After the table has been 75 moved by hand to the desired position, the power mechanism may then be thrown into action by throwing out the hand operating mechanism by means of the lever 78 and throwing the power mechanism into operation. During this latter movement of the hand lever 78 the slide frame 62 will be released, by reason of the arm 91 becoming disengaged from the pin 93 and the arm 72 becoming again engaged with the pin 70 85 which will correctly position and lock the rocking frame 67.

Having thus described my invention, what I claim and desire by Letters Patent to secure is:

1. An apparatus of the class described having, in combination, a rotary driving member, a reciprocatory driven member co-acting with said driving member and driven thereby, a pin upon which said driving member is mounted, means to impart a rotary motion to said driving member and means to impart a lateral movement to said pin, whereby the reciprocatory movement of said driven member may be controlled. 90

2. An apparatus of the class described having, in combination, a rotary driving member, a reciprocatory driven member co-acting with said driving member and driven thereby, a rock-shaft, an eccentric pin on 95 said rock-shaft upon which said driving member is rotatably mounted, means to rotate said driving member and means to rock said rock-shaft, whereby a lateral movement may be imparted to said eccentric pin and the reciprocatory movement of said driven member be controlled. 105

3. An apparatus of the class described having, in combination, a reciprocatory driven member, a rack fast thereto, a gear meshing 110 with said rack, a worm gear fast to said gear, a pin upon which said gear and worm gear are rotatably mounted, a worm meshing with said worm gear, mechanism adapted to rotate said worm and means to impart a lateral movement to said pin, whereby the reciprocatory movement of said driven member may be controlled. 115

4. An apparatus of the class described having, in combination, a reciprocatory 120 driven member, a rack fast thereto, a gear meshing with said rack, a worm gear fast to said gear, a rock-shaft, an eccentric pin on said rock-shaft upon which said gear and worm gear are rotatably mounted, a worm 125

meshing with said worm gear, mechanism adapted to rotate said worm and means to rock said rock-shaft, whereby a lateral movement may be imparted to said eccentric pin 5 and the reciprocatory movement of said driven member be controlled.

5. An apparatus of the class described having, in combination, a reciprocatory driven member, a rack fast thereto, a gear 10 meshing with said rack, a worm gear fast to said gear, a rock-shaft, an eccentric pin on said rock-shaft upon which said gear and worm gear are rotatably mounted, a worm meshing with said worm gear, mechanism 15 adapted to rotate said worm and a cam lever operatively connected with said rock-shaft adapted to be moved to rock said rock-shaft, whereby a lateral movement may be imparted to said eccentric pin and the reciprocatory 20 movement of said driven member controlled.

6. An apparatus of the class described having, in combination, a table, means for reciprocating said table including a gear, a worm adapted to rotate said gear, a clutch 25 adapted to be operated to rotate said worm in opposite directions, means operated by said table adapted to move said gear laterally of its axis to neutralize the effect of said worm upon said gear and means operated 30 by said gear moving means during the neutralizing action thereof adapted to shift said clutch and reverse the action of said worm.

7. An apparatus of the class described 35 having, in combination, a table, means for reciprocating said table including a gear, a worm adapted to rotate said gear, means for reversing the action of said worm, a pin upon which said gear is rotatably mounted, 40 and means operated by said table adapted to move said pin laterally thereof in a direction reverse to that of said table, whereby the effect of said worm upon said gear will be neutralized.

45 8. An apparatus of the class described having, in combination, a reciprocating member, means for reciprocating said member including a gear, a pin upon which said gear is rotatably mounted, a worm adapted 50 to rotate said gear, a pivoted cam, a rock-shaft upon which said pin is eccentrically mounted adapted to be rocked by said cam, whereby said pin may be moved laterally thereof to neutralize the effect of said worm 55 upon said gear, means for rotating said worm in opposite directions, a clutch adapted to be shifted from one of said worm rotating means to the other to reverse the action of said worm and means operated by 60 said reciprocating member adapted to shift said clutch.

9. An apparatus of the class described having, in combination, a reciprocating member, a gear operatively connected with said 65 reciprocating member, a pin upon which

said gear is rotatably mounted, a worm adapted to rotate said gear, forward and reverse driving means for said worm, a clutch adapted to be moved to connect said worm either with said forward driving 70 means or with said reverse driving means and means operated by said reciprocating member adapted to shift said clutch from one of said driving means to the other and for moving said pin laterally thereof immediately prior to the shifting of said clutch and immediately following the shifting of said clutch.

10. An apparatus of the class described having, in combination, a gear, a pin upon 80 which said gear is rotatably mounted, a worm adapted to rotate said gear, forward and reverse driving means for said worm, means to automatically shift from one of said driving means to the other, and means 85 adapted to move said pin laterally thereof in one direction prior to the shift from one of said driving means to the other and to move said pin laterally thereof in the opposite direction immediately following said shift. 90

11. An apparatus of the class described having, in combination, a gear, a pin upon which said gear is rotatably mounted, a worm adapted to rotate said gear, forward and reverse driving means for said worm, a 95 clutch adapted to operatively connect said worm with one or the other of said driving means, means for automatically shifting said clutch and means for moving said pin laterally thereof and immediately prior to 100 the shifting of said clutch.

12. An apparatus of the class described having, in combination, a gear, a pin upon which said gear is rotatably mounted, a worm adapted to rotate said gear, forward 105 and reverse driving means for said worm, a clutch adapted to operatively connect said worm with one or the other of said driving means, means for automatically shifting said clutch, and means for moving said pin laterally thereof in one direction prior to the shifting of said clutch and in the opposite direction immediately following the shifting of said clutch. 110

13. A device of the character described 115 having, in combination, a table, means to impart a reciprocatory motion to said table including a gear, a rock-shaft, an eccentric pin on said rock-shaft upon which said gear is rotatably mounted, a rocker arm fast to 120 said rock-shaft and a cam lever adapted to rock said rocker arm whereby a lateral movement may be imparted to said pin.

14. A device of the character described 125 having, in combination, a table, means to impart a reciprocatory motion to said table including a gear, a rock-shaft, an eccentric pin on said rock-shaft upon which said gear is rotatably mounted, a rocker arm fast to said rock-shaft, a cam lever adapted to rock said 130

6
rocker arm, and tappets on said table adapted to alternately rock said cam lever in opposite directions, whereby said pin may be laterally moved in opposite directions.

- 5 15. A device of the character described having, in combination, a table, means to impart a reciprocatory motion to said table including a gear, a rock-shaft, an eccentric pin on said rock-shaft upon which said gear is 10 rotatably mounted, a rocker arm fast to said rock-shaft, a cam lever adapted to rock said rocker arm, tappets on said table adapted to alternately rock said cam lever in opposite directions, whereby said pin may be laterally moved in opposite directions, and yielding means arranged on opposite sides of the pivot of said lever adapted to alternately return said lever to a central position.

- 20 16. An apparatus of the class described having, in combination, a rotary driving member, a reciprocatory driven member co-acting with said driving member and driven thereby, power driven mechanism adapted to rotate said driving member, mechanism adapted to impart a movement to said driving member laterally of its axis of rotation, manually operated mechanism adapted to rotate said driving member and means to alternately throw said power driven and 30 manually driven mechanisms into and out of operation.

- 25 17. An apparatus of the class described having, in combination, a rotary driving member, a reciprocatory driven member co-acting with said driving member and driven thereby, mechanism adapted to rotate said rotary member and mechanism adapted to impart a movement to said rotary member laterally of and including its axis of rotation, whereby the reciprocatory movement of said reciprocatory member may be controlled.

- 40 18. An apparatus of the class described having, in combination, a rotary driving member, a reciprocatory driven member co-acting with said driving member and driven thereby, mechanism adapted to rotate said driving member alternately in opposite directions and mechanism adapted to impart a lateral movement to said driving member alternately in opposite directions and laterally of and including its axis of rotation, whereby the movement of said driven member may be controlled at opposite ends of its reciprocatory movement.

- 45 19. An apparatus of the class described having, in combination, a rotary driving member, a reciprocatory driven member co-acting with said driving member, mechanism adapted to rotate said driving member and mechanism actuated by said driven member adapted to move said driving member laterally of and including its axis of rotation.

- 50 20. An apparatus of the class described having, in combination, a rotary driving

member, a reciprocatory driven member co-acting with said driving member and driven thereby, reversing mechanism adapted to alternately rotate said driving member in opposite directions and mechanisms actuated by said driven member adapted to operate said reversing mechanism and adapted to move said driving member alternately in opposite directions and laterally of and including its axis of rotation.

75 21. An apparatus of the class described having, in combination, a rotary driving member, a reciprocatory driven member co-acting with said driving member and driven thereby, power driven mechanism adapted to 80 rotate said driving member alternately in opposite directions and mechanism adapted to impart a lateral movement to said driving member alternately in opposite directions and laterally of its axis of rotation, manually operated mechanism adapted to rotate said driving member and means adapted to alternately throw said power driven and manually driven mechanisms into and out of operation.

85 22. An apparatus of the class described having, in combination, a rotary driving member, a reciprocatory driven member co-acting with said driving member and driven thereby, power driven reversing mechanism adapted to alternately rotate said driving member in opposite directions, mechanisms actuated by said driven member adapted to operate said reversing mechanism and adapted to move said driving member laterally of its axis of rotation alternately in opposite directions, manually operated mechanism adapted to rotate said driving member and means adapted to alternately throw said power driven and manually driven mechanisms into and out of operation.

90 23. An apparatus of the character described having, in combination, a gear, a worm adapted to rotate said gear, forward and reverse driving means for said worm, a 110 slide, means operated by said slide adapted to shift from one of said driving means to the other, a cam member movable relatively to said slide, yielding means interposed between said cam member and said slide and adapted to be compressed by the movement of said cam member, and means to lock said slide against movement thereof by said yielding means, said locking means adapted to be released by said cam member to allow 115 said slide to be moved by said yielding means in opposite directions.

120 24. An apparatus of the character described having, in combination, a gear, a worm adapted to rotate said gear, forward and reverse driving means for said worm, a slide, means operated by said slide adapted to shift from one of said driving means to the other, a cam member movable relatively to said slide, yielding means interposed 130

between said cam member and said slide and adapted to be compressed by the movement of said cam member, a rocker frame, means to lock said rocker frame in a stationary position, and means mounted on said rocker frame to lock said slide against movement thereof by said yielding means, said locking means adapted to be released by said cam member to allow said slide to be moved by said yielding means in opposite directions.

25. An apparatus of the class described having, in combination, a table, means for reciprocating said table including a gear, a worm adapted to rotate said gear, forward and reverse driving means for said worm, a clutch adapted to operatively connect one or the other of said driving means with said worm, a slide connected to said clutch and adapted to shift said clutch from one to the other of said driving means, a cam member movable relatively to said slide, yielding means interposed between said cam member and said slide and adapted to be compressed by the movement of said cam member, a rocker frame, means to lock said rocker frame in a stationary position, means mounted on said rocker frame adapted to lock said slide against movement thereof by said yielding means, said locking means adapted to be released by said cam member to allow said slide to be moved by said yielding means and thus to move said clutch in opposite directions, and manually operated means adapted to lock said slide with said clutch in neutral position and to unlock said rocker frame.

26. An apparatus of the class described having, in combination, a table, means for reciprocating said table including a gear, a worm adapted to rotate said gear, forward and reverse driving means for said worm, a clutch adapted to operatively connect one or the other of said driving means with said worm, a slide connected to said clutch and adapted to shift said clutch from one to the other of said driving means, a cam member movable relatively to said slide, yielding means interposed between said cam member and said slide and adapted to be compressed by the movement of said cam member, a rocker frame, means to lock said rocker frame in a stationary position, means mounted on said rocker frame adapted to lock said slide against movement thereof by said yielding means, said latter locking means adapted to be released by said cam member to allow said slide to be moved by said yielding means and thus to move said

clutch in opposite directions, and manually operated means adapted to lock said slide with said clutch in neutral position and to unlock said rocker frame, said manually operated means adapted to position and lock said rocker frame in position and to unlock said slide to allow the same to be operated by said yielding means.

27. An apparatus of the class described having, in combination, a table, means for reciprocating said table including a gear, a worm adapted to rotate said gear, forward and reverse driving means for said worm, a clutch adapted to operatively connect one or the other of said driving means with said worm, a movable cam member adapted to be operated in opposite directions by said table and means operatively connecting said cam member with said gear and said clutch adapted to control the effect of said gear upon said table and shift said clutch.

28. An apparatus of the class described having, in combination, a table, means for reciprocating said table including a gear, a worm adapted to rotate said gear, forward and reverse driving means for said worm, a clutch adapted to operatively connect one or the other of said driving means with said worm, a movable cam member adapted to be operated in opposite directions by said table, means for yieldingly maintaining said cam in its central position and means operatively connecting said cam member with said gear and said clutch adapted to control the effect of said gear upon said table and shift said clutch.

29. An apparatus of the class described having, in combination, a table, means for reciprocating said table including a gear, a worm adapted to rotate said gear, forward and reverse driving means for said worm, a clutch adapted to operatively connect one or the other of said driving means with said worm, a movable cam member adapted to be operated in opposite directions by said table, a pair of oppositely disposed spring-actuated contact members adapted to centralize said cam member and means operatively connecting said cam member with said gear and clutch adapted to control the effect of said gear upon said table and shift said clutch.

In testimony whereof I have hereunto set my hand in presence of two subscribing witnesses.

WARREN F. FRASER.
